J. ZOULEK,
COMBINED PORCH SWING AND INVALID COUCH.
APPLICATION FILED DEC. 30, 1919.

1,366,625.

Patented Jan. 25, 1921.

UNITED STATES PATENT OFFICE.

JOSEPH ZOULEK, OF EAST JORDAN, MICHIGAN.

COMBINED PORCH-SWING AND INVALID-COUCH.

1,366,625.

Specification of Letters Patent. Patented Jan. 25, 1921.

Application filed December 30, 1919. Serial No. 348,274.

To all whom it may concern:

Be it known that I, JOSEPH ZOULEK, a citizen of the United States, residing at East Jordan, in the county of Charlevoix and State of Michigan, have invented certain new and useful Improvements in Combined Porch-Swings and Invalid-Couches; and I do hereby declare the following to be a full, clear, and exact description of the invention, such as will enable others skilled in the art to which it appertains to make and use the same.

This invention relates to improvements in what may be termed combined porch-swings and couches, particularly adapted for invalids and convalescents.

The invention has for its object to provide an article of furniture of the aforesaid type which shall be simple, of few parts which are readily assembled and disconnected, and which device or article is capable of ready actuation by hand or foot of the occupant.

A further object of the invention is to provide for its ready conversion into its several utilities, as for instance, into a porch-swing or into a couch.

A further object of the invention is the devising thereof so as to reduce friction and wear to the minimum, and not to require the application of lubricants thereto.

A still further object is to provide for so organizing the parts of the invention or device, whereby it may be readily maintained in a sanitary condition or cleanly.

A still further object is to render the invention adaptable to readily conform to the posture or position of the occupant for bodily comfort.

Other objects or advantages of the invention will be made apparent from the following description thereof.

In the accompanying drawing is illustrated the preferred embodiment of my invention wherein it will be understood that various changes and modifications as to the detailed construction and arrangement of parts may be made without departing from the spirit or scope of the invention as embraced in the appended claims.

50 In the drawings:

Figure 1 is a side elevation of my invention, improved combined porch-swing and couch;

Fig. 2 is a vertical longitudinal section thereof;

Fig. 3 is a central transverse section of the same.

In carrying out my invention I provide two principal members, preferably in the form of rectangular frames 1 and 2, adapted for positioning or superposing one upon the other, the lower longitudinal bars of the lower, or what may be termed the base-frame (1) being preferably reduced longitudinally, intermediate of their ends, to lessen contacting surface thereof with the floor, which is quite common, for obvious reasons.

Upon the inner sides of the longitudinal bars of both the base frame or members 1 and the upper frame or member 2 are suitably secured, preferably by screw-headed bolts and nuts 3, 3^a, pairs of what may be designated as rails 4, each pair of rails of one frame being arranged in vertical alignment with respect to the opposed pairs of rails of the other frame, as clearly understood especially from Figs. 2 and 3. These rails, which are preferably of steel, are contoured in arcuate-formation as shown, and suitably spaced off from the longitudinal bars of the frames for reasons presently made apparent, and have their vertically alining concave surfaces presented toward each other, the purpose of which will be seen later.

Suitable wheels or trucks 5, connected together in pairs, each pair preferably by an axle forming steel rod 6, are arranged to freely travel between the pairs of arcuate rails 4, said wheels or trucks being provided with circumferential grooves 5^a which receive the rails 4, for the retention of the wheels thereon, as against inadvertent displacement, no other means, however, being interposed therebetween for that purpose. Each of the axle-forming rods 6, it will be seen, is wholly independent of other bearings than the wheels or trucks 5, with which they travel, having no connection with any other part. It will therefore be apparent that as the upper frame member is oscillated, which may be done, say with a person suitably seated thereon and applying foot-pressure to a fixed point, as for instance to the board or part 6 carried by the base frame 1, a rotary movement of the wheels

5 will be caused by reason of their coöperation with the rails 4, and the arcuate contour or curvature of the rails will cause a gentle swinging movement of the couch-carrying member or frame.

The upper frame or member 2 has also suitably supplied thereto seats 7, one at each end, the members of which, as the back and seat boards 7^a, 7^b, respectively, are 10 adaptable to be disposed at suitable angles as shown, either for sitting or recumbent purposes as in effecting the conversion of the device into a couch or swing, as is readily appreciable. Any suitable means may be 15 employed for disposing and retaining the parts in the angular positions indicated, as set or adjusting screws, examples of which in somewhat primitive form are disclosed at 8.

20 It is further observed that by reason of the several principal constituent parts of my invention being so constructed and arranged as not to require any means of connection therebetween, said parts are readily separable and accordingly are readily and quickly taken apart for transference, and thereafter as quickly reassembled for use.

From the foregoing it is considered that the various advantages and utilities for 30 which my invention is adaptable have been made plain, and therefore, do not call for further elaboration herein.

Having thus described my invention, what I claim and desire to secure by Letters Patent is;

1. A combined swing and couch, including a base member and an upper superposed member, said members being provided with pairs of arcuate rails, with their

concavities presented toward each other, and 40 rotary members connected in pairs and co-operatively associated with said pairs of rails, the axle-forming members of said rotary members being wholly independent of other means of support than the rotary 45 members which they carry.

2. A device of the type described, including a base-member and an upper or superposed member each being provided with a plurality of pairs of rails of arcuate outline, and pairs of axle-connected rotary members having circumferential grooves adapted to receive said rails, said rotary members being adapted to travel intermediate of said rails, the axle-forming members 50 of said rotary members being wholly independent of other means of support than the rotary members which they carry.

3. A device of the type described, including vertically aligned members provided with 60 pairs of arcuate rails, the upper one of said aligned members being provided with end-seats and a foot engaged member intermediate of said seats, and axle-connected pairs of rotary members provided with circumferential grooves adapted to receive said rails, said rotary members being arranged between pairs of said rails, the axle-forming members of said rotary members being wholly independent of other means of support 65 than the rotary members which they carry.

In testimony whereof, I affix my signature.

JOSEPH ZOULEK
